(No Model.)

J. APPLEBAKER.
SLEIGH KNEE.

No. 439,370.

Patented Oct. 28, 1890.

Fig. 1.

Fig. 3.

UNITED STATES PATENT OFFICE.

JOSEPH APPLEBAKER, OF MARSHFIELD, WISCONSIN.

SLEIGH-KNEE.

SPECIFICATION forming part of Letters Patent No. 439,370, dated October 28, 1890.

Application filed October 22, 1888. Serial No. 288,780. (No model.)

To all whom it may concern:

Be it known that I, JOSEPH APPLEBAKER, of Marshfield, in the county of Wood, and in the State of Wisconsin, have invented certain new and useful Improvements in Sleigh-Knees; and I do hereby declare that the following is a full, clear, and exact description thereof.

My invention relates to sleigh-knees, and will be fully described hereinafter.

In the drawings, Figure 1 is a side elevation of a sleigh-knee embodying my invention. Fig. 2 is a plan view, and Fig. 3 a vertical section on line 3 3, Fig. 2.

15 A are the runners, and B are the knees. These knees are preferably of cast metal, each having a central pillow that is braced front and rear by struts a a, which are cast with it. The base b of the knee is formed with depending-lugs c, that straddle the runner and receive bolts d, that secure the knee to the runners. Horizontal ears e project from the front and rear of the base, and each is formed with an opening to fit over a dowel-pin e', that projects 25 up from the runner. These pins not only serve to fix the knee in position to bring the bolt-holes in the ears d flush with the proper holes in the runner, but also serve to resist strain on the struts a.

30 The upper end of the central pillow of each knee is bifurcated to form standards f f, each pair of standards receiving between them an end of the bolster C. The inner face of each standard is formed with a rib g, and the bolster is correspondingly grooved, and by the

engagement of these ribs with the grooves in the bolster the runners are held together. The ends of the bolsters are held down by overlying straps h, that are secured to the knees by bolts i.

40 The castings forming the knees may be made light or heavy, as the necessities of the case may require.

45 My improved knee is durable and can be cheaply constructed.

Having thus fully described my invention, what I claim as new, and desire to secure by Letters Patent, is—

50 In a sleigh-knee, the combination, with the runner of a sleigh having dowel-pins projecting from its upper side, of a knee having horizontal extensions or ears to receive said dowel-pins, vertically-pendent lugs for straddling the runner, vertical standards ribbed on their inner sides, oblique struts extending from the 55 upper ends of the standards and downward to the upper side of the knee, and a strap attached at its ends to the oblique braces and overlaying the bolster so as to confine the end of the bolster between the standards, substantially as described.

55 In testimony that I claim the foregoing I have hereunto set my hand, at Marshfield, in the county of Wood and State of Wisconsin, in the presence of two witnesses.

JOSEPH APPLEBAKER.

Witnesses:

FRANK A. CADY,
FRED VOLLENOR.
